United States Patent Office.

JOHN S. INSKEEP, OF WEST MIDDLEBURG, OHIO.

Letters Patent No. 73,810, dated January 28, 1868.

IMPROVED SUGAR-MOULD.

The Schedule referred to in these Letters Patent and making part of the same.

TO ALL WHOM IT MAY CONCERN:

Be it known that I, JOHN S. INSKEEP, of West Middleburg, Logan county, State of Ohio, have invented a new and improved Sugar-Mould; and I do hereby declare the following description and accompanying drawings are sufficient to enable any person skilled in the art or science to which it most nearly appertains to make and use my said invention or improvements without further invention or experiment.

The nature of my invention and improvement consists in constructing a mould for forming blocks or cakes of maple, sorghum, and other sugars, by providing a frame or box, without bottom, of wood or other suitable material, and square, oblong, or polygonal in shape, and then cutting and bending a piece of tin or other sheet metal so as to form a complete box, just fitting into the frame aforesaid, but with the sides and ends loose or detached from each other, being held in place by the frame to receive the liquid sirup, but readily springing off when it has cooled and become solid, and the box is removed from the frame, thus releasing at once the cake formed, the bottom of the box being supported free from contact with any surface, so as to allow a free circulation of air beneath, to hasten the cooling and hardening of the sirup.

In describing my improved mould, I refer to the accompanying drawings, forming part of this specification—

Figure 1 being an elevation of the frame.

Figure 2, a plan of the same.

Figure 3 shows the shape into which the sheet metal is to be cut to form a box for an oblong frame, as here shown; and

Figure 4 is a plan of the box formed.

The frame or case A may be made of the size desired, and a piece of sheet metal is then marked, and the corners cut out, as shown in fig. 3, the central division being made to correspond to the inside length and width of the frame and the wings, out to the exterior dotted lines, with the dimensions of the sides and ends respectively of the same.

To form the sides and ends of the box, the wings are bent up at the interior dotted lines, at right angles to the central portion or bottom, and the top edges are bent outward at right angles, and thus is formed the complete box B, shown in fig. 4. As the vertical corners of the box B are not soldered, but loose or detached, it is slipped into the frame or case A, in order that it may hold safely the liquid sirup. Its position in the frame is shown by dotted lines in fig. 2, the horizontal projecting edges resting on the frame, and preventing the box from slipping through.

The bottom of the box should be supported free from contact with any surface, and a free circulation of air allowed beneath it, to hasten the cooling and hardening of the sirup. This may be effected by giving extra depth either to the sides or to the ends, or by blocks or supports attached to the bottom of the sides or ends of the frame, as shown in fig. 1, or the frame itself may be placed on the edges of strips or rails provided for that purpose.

As soon as the sirup has cooled and become solid sugar, the frame may be turned over, and the box pushed out, and the loose sides and ends cleaving off from the cake or block of sugar, it is at once set free, and may be removed.

The frame A may be made triangular, hexagonal, octagonal, or of any polygonal form desired, and the sides may be made oblique or flaring, and the tin must then be cut and bent so that the box formed of it may just fit into the frame.

I claim a sheet-metal box B, having its vertical corners loose or detached, in combination with a frame, A, into which it fits, and within which it is supported by its horizontal edges or flanges, substantially as described, and for the purposes set forth
